UNITED STATES PATENT OFFICE.

HAROLD D. WATERHOUSE, OF QUINCY, MASSACHUSETTS, ASSIGNOR, BY MESNE ASSIGNMENTS, TO WALTER S. CRANE, JOSHUA CRANE, AND FRANK V. STONE, TRUSTEES.

PRIMER FOR INTERNAL-COMBUSTION ENGINES.

1,421,627.

Specification of Letters Patent.

Patented July 4, 1922.

Application filed December 17, 1917. Serial No. 207,592.

To all whom it may concern:

Be it known that I, HAROLD D. WATERHOUSE, a citizen of the United States, residing at Wollaston, city of Quincy, county 5 of Norfolk, and State of Massachusetts, have invented an Improvement in Primers for Internal-Combustion Engines, of which the following description, in connection with the accompanying drawings, is a specification, like characters on the drawings representing like parts.

This invention relates to improvements in primers for internal combustion engines, and more particularly, though not exclusively, to a primer adapted to supply to the intake manifold of an engine a very fine mist or vapor of carbureted hydrocarbon to facilitate starting the engine.

In the drawings in which I have shown an 20 illustrative embodiment of a preferred form of my invention:—

Fig. 1 is a side elevation of an internal combustion engine having a preferred form of primer applied thereto;

Figs. 2 and 3 are longitudinal central sections through the preferred form of primer, showing parts of different relative positions more fully described hereafter; and

Fig. 4 is a section on the line 4—4 of 30 Fig. 2.

Referring to the drawings, I have shown an internal combustion engine 1 having any usual or known construction, said engine being equipped with a carburetor 2 to which gasoline is supplied through a gasoline supply pipe 3, and also having an intake pipe 4 leading from the carburetor and through which the combustible charge from the carburetor is delivered to the engine. These 35 elements may have any suitable or known construction. The improved primer is adapted to be applied to the intake pipe 4 or to any portion of the intake passage between the throttle of the carburetor 2 and the inlet 40 ports of the engine, and is constructed to deliver into the intake passage a readily ignitable, completely vaporized priming charge whenever it is desired to prime the engine.

The primer is adapted for use in connection 50 with any internal combustion engine whether it burns gasoline or any other fuel or combination of fuels which can be used in internal combustion engines. I will, however, for

convenience refer to the fuel as gasoline, although I do not wish to limit the use of my device to an engine which burns gasoline.

The preferred form of primer preferably comprises a valve device having an air passage therein adapted to communicate with the intake pipe, said passage preferably being contracted in cross-section at some portion of its length, and preferably being provided with a duct or port communicating with a source of gasoline supply preferably leading into the passage at its contracted portion. I preferably provide means whereby both the passage and the duct may be opened and closed. If the engine is cranked while the passage and duct are opened a current of air will be drawn through the passage into the intake pipe by the suction produced in the engine.

The gasoline supply line to the primer is preferably connected to the main gasoline supply of the engine, and I prefer to locate the primer in such position that gasoline will enter the primer if the valve is opened whether or not the engine is being cranked, thus providing a gasoline supply to the primer independent of engine suction. 75 Thus, if used in connection with a gravity gasoline feed system, I preferably locate the primer at such height that gasoline will flow to the primer. I do this because it is much easier and quicker for the engine suction to raise a mixture of air and liquid fuel than for the engine to raise by suction a column of liquid fuel unmixed with air. The shape of the passage is preferably such that the movement of the air through the contracted portion will be a very rapid or violent one 80 which will operate to completely atomize and vaporize the gasoline, thus producing a readily ignitable fuel charge.

The valve device may be constructed in various ways and yet embody the above principle of operation. The preferred form of valve device shown in the drawings comprises a valve casing 5 which may be secured directly to the intake pipe 4 of the internal combustion engine, and which is provided with a delivery port 6 leading into the intake pipe 4, and with an air inlet port 7. The preferred form of valve also provides a nozzle 8 having a duct 9 therethrough 100 which communicates with a gasoline supply

pipe 10 that leads to any suitable source of gasoline supply, but which is preferably connected to the gasoline pipe 3 which supplies gasoline to the carburetor 2, as shown in Fig. 1. The valve casing 5 is provided with a chamber 11 in which is received a plug or valve member 12, said plug preferably being adapted to be moved longitudinally of the chamber from the position shown in Fig. 2 to that shown in Fig. 3. This valve member is provided with a transverse passage 13 which is adapted to connect the inlet port 7 and discharge port 6 when the valve device is moved into the position shown in Fig. 3. The plug or valve 12 is provided in one end with a recess 14 in which the nozzle 8 is received, and said nozzle is of such length that when the valve or plug 12 is moved into the position shown in Fig. 3 thereby to bring the transverse port 13 into communication with the ports 6 and 7, the end or tip of the nozzle 8 will be situated approximately in line with the wall of the port 13, so that the duct 9 communicates with the port. Seated in the inner end of the recess 14 is a plug or valve seat 15 of some relatively soft material such as fiber, brass, copper, etc., which is adapted to seat against the end of the nozzle 8 and thereby close the duct 9 when the valve member 12 is in the position shown in Fig. 2. In this position of the valve member, the port 13 is out of line with the ports 6 and 7.

The ports 6, 13 and 7 constitute an air passage through which air may be drawn into the intake passage leading from the carburetor to the inlet ports of the engine when the valve member is in the position shown in Fig. 3, and the portion 13 of said passage is preferably of less cross-sectional area than the portions 6 and 7. The plug or valve member 12 preferably constitutes means by which this air passage may be opened and closed, the air passage being closed when the valve member is in the position shown in Fig. 2 and being opened when the valve member is in the position shown in Fig. 3. The nozzle 8 is so arranged that when the valve member 12 is in position to close the air passage, the gasoline supply duct will also be closed by the plug 15 which seats against the end of the nozzle, while when the valve member 12 is moved to open the air passage, the gasoline supply duct is also open and communicates with the air passage at its contracted portion 13.

The valve member 12 is acted upon by a suitable spring 16 which tends normally to maintain it in position to close the air passage and gasoline duct. Said valve member is provided with a stem 17 which projects through the casing 5 and to which is connected a cord or other flexible connection 18 leading to a knob or handle 19 which may be situated in any convenient position. In

the case of an internal combustion engine for an automobile, the cord 18 will be preferably carried to the dash-board or instrument-board 20 of the automobile, so that the pull 19 can be readily actuated by the operator.

When it is desired to prime the engine, the valve member 12 is pulled into the position shown in Fig. 3 against the action of the spring 16, thereby opening both the air passage and the gasoline duct 9. When the engine is cranked, the suction produced thereby will draw air through the air passage into the intake pipe and, because the air passage is contracted at the portion 13, the movement of the air current through this contracted portion will be a rapid or violent one. This movement of the air creates considerable suction at the end of the duct 9 which causes gasoline to be drawn into the air passage, and because of the violent and rapid movement of the air through the contracted portion 13, the liquid gasoline thus delivered to the intake passage is completely broken up into a fine mist or vapor which becomes thoroughly commingled with the air and thus produces a readily ignitable mixture. The gasoline duct is much smaller in cross-section than the contracted portion of the air passage, and the size of the duct and air passages are so proportioned as to produce a mixture having the proper proportions of air and gasoline vapor to produce an easily ignitable charge.

After the engine has started, the valve member or plug 12 is allowed to return to the position shown in Fig. 2, thereby closing both the air passage and the gasoline supply duct. The engine will then receive its explosive charges from the carburetor in usual manner.

The valve member 12 is held from turning movement in the chamber 11 by some suitable means. In the construction shown the stem 17 of the plug is non-circular and extends through a non-circular opening in the end of the casing 5.

The inlet port 7 of the air passage as herein shown is preferably provided with an inwardly-opening check valve 21 which is acted upon by a spring 22 that normally holds it to its seat. This check valve allows the air to be freely drawn into the air passage, but prevents the air or charge from being forced out through the air passage if the engine has a slight backward movement during the cranking operation.

In the preferred form of my invention, the port 6 is preferably closed after the engine has started, and so long as it is running in order to prevent air from being drawn in through said port, and I may render the closure particularly tight by providing the plug 12 with a split resilient band 23 preferably of cork, which fits closely the walls 130

of the chamber 11. The band 23 is of such size and is so situated that when the plug 12 is in the position shown in Fig. 2, said band completely covers and thereby closes 5 the port 6. This band is confined between an annular shoulder 24 formed on the plug 12 and a washer 25 against which the spring 16 acts.

If the plug 12 is made to fit the chamber 10 11 tightly enough, it may not be necessary to use the band 23. The latter, however, acts somewhat in the nature of a piston ring and provides for producing a tighter fit. This band 23 is preferably held in proper position by means of a pin 26 carried by the 15 plug 12 and extending into an opening 27 formed in the band.

The device can be readily installed on any 20 internal combustion engine, and is extremely effective in delivering to the engine a priming charge having the proper proportions of air and gasoline and also having the gasoline in completely vaporized form so that the charge is readily ignitable. An internal 25 combustion engine equipped with this device can be readily started when cold without the necessity of continual cranking.

While I have shown and described a preferred form of one embodiment of my invention, it will be understood that major 30 changes involving omission, alteration, substitution, and reversal of parts, and even changes in mode of operation, may be made without departing from the scope of my invention, which is best defined in the following 35 claims.

Claims:

1. A primer for internal combustion engines comprising a valve device having an 40 air passage which is contracted at some portion of its length and is adapted to be registered by operator controlled means with the intake pipe of the engine, a gasoline supply duct which is arranged to communicate 45 with said contracted portion, said valve device constituting means to open and close said passage and duct.

2. A primer for internal combustion engines comprising a valve casing having an 50 air inlet port and a discharge port adapted to communicate with the intake passage of said engine, a valve member movably mounted in said casing and having therein a port which is adapted to be brought into and out 55 of register simultaneously with both the ports of the casing, said casing being provided with a gasoline supply duct arranged to have communication with the port in the valve member when the latter communicates 60 with the ports in the casing, said valve member having provision for closing said duct only when the port therein is out of register with the ports in the casing, and means for limiting movement of the valve within the 65 casing so that it moves only between the

position in which the ports and duct are closed and the position in which the ports and duct are open.

3. In a primer for internal combustion engines, the combination of a valve device having an air passage which is contracted at some portion of its length to form substantially a Venturi passage and which communicates with the intake passage of the internal combustion engine, a relatively small 70 fuel supply duct adapted to open adjacent the contracted portion of said passage and connected to a source of fuel supply, and a movable member adapted in one position to close both said air passage and said duct and 75 in another position to open said air passage and said duct.

4. A primer for internal combustion engines comprising a valve casing having an air inlet port, a discharge port and a nozzle 85 through which gasoline is delivered to the casing, a valve member mounted in said casing and provided with a port, said valve member being movable from closed position in which the port therein is out of register 90 with the inlet and discharge ports into open position in which the port therein is in register with said inlet and discharge ports, said valve member also having a recess to receive said nozzle and to close the nozzle when the 95 valve member is in closed position, said recess communicating with the port in the valve member.

5. A primer for internal combustion engines comprising a valve casing 5, a valve 100 member 12 mounted in the valve casing, said valve member being provided with a Venturi passage 13 and a recess 14, and a nozzle 8 received within the recess when the valve member is in closed or cut-off position and 105 adapted to deliver liquid fuel to the air drawn through the Venturi passage 13 when the valve member is in open position.

6. A priming apparatus for internal combustion engines comprising, in combination, 110 a carburetting device for delivering carburetted air to the intake passage of the engine independently of the main carburetor of the engine, said device including a passage for the admission of air to the intake 115 manifold of the engine, which passage has a restricted portion of invariable dimensions, a more restricted gasoline supply duct discharging fuel adjacent the restricted portion of the passage, and means for opening and 120 closing said duct.

7. A priming apparatus for an internal combustion engine comprising, in combination, a carbureting device for delivering carbureted air to the intake passage of the engine, independently of the main carburetor of the engine, said device including a restricted passage for the admission of engine suction-actuated air to the intake passage of the engine, a more restricted gasoline supply 125 130

duct entering at the side of said restricted passage, and means for co-ordinately controlling the opening and closing of said duct and said passage.

- 5 8. In a primer for internal combustion engines, in combination, a body including a valve chamber having a valve slideable therein, an air passage provided in the body at right angles to the valve chamber and opening into the chamber, a check valve adapted to close automatically the inlet end of the

air passage, a liquid fuel duct opening into the air passage in such position that it is in the path of a current of air passing through said passage, said valve in one position closing both the passage and the duct and in another position permitting free flow of air through the body. ¹⁵

In testimony whereof, I have signed my name to this specification.

HAROLD D. WATERHOUSE.
